PERMUTATION LOCK

Raymond A. Cruse, South Pekin, Ill.

Application May 23, 1932, Serial No. 613,077

1 Claim. (Cl. 70—53)

This invention relates to certain novel improvements in permutation locks, and has for its principal object the provision of an improved construction of this character which will be

5 highly efficient in use and economical in manufacture.

The invention herein described represents an improvement over the structure disclosed in my U. S. Patent No. 1,834,901, dated December 1,

10 1931.

Objects of the present invention are: to improve upon the means shown in my said patent for securing the lock casing sections together against unauthorized separation; to improve 15 upon the construction of the tumblers shown in my aforesaid patent; to improve upon the supporting member and sleeve for retaining the tumblers, carriers, and combination rings upon the core or supporting member; and to improve 20 generally upon the lock structure shown in my patent hereinbefore identified.

Other objects will appear hereinafter.

The invention consists in the novel combination and arrangement of parts to be hereinafter 25 described and claimed.

The invention will be best understood by reference to the accompanying drawings showing the preferred form of construction, and in which:

30 Fig. 1 is an elevational view, partly in section, illustrating a typical use of the invention;

Fig. 2 is an elevational view of the invention; Fig. 3 is a sectional view on line 3—3 in Fig. 2;

Fig. 4 is a sectional view on line 4—4 in Fig. 3;

35 Fig. 5 is a sectional view on line 5—5 in Fig. 3; Fig. 6 is a sectional view on line 6—6 in Fig. 3;

Fig. 7 is a bottom plan view, partly in section, on line 7—7 in Fig. 3;

40 Fig. 8 is a perspective view of one of the improved lock casing sections;

Fig. 9 is a perspective view of the other of the improved lock casing sections;

Fig. 10 is a perspective view of the improved core or supporting member;

45 Fig. 11 is a perspective view of the improved locking bolt;

Fig. 12 is a perspective view of one of the combination rings;

50 Fig. 13 is a perspective view of one of the improved tumblers;

Fig. 14 is a perspective view of one of the tumbler carriers;

55 Fig. 15 is a perspective view of the improved retaining sleeve;

Fig. 16 is an elevational view illustrating another typical use of the invention; and

Fig. 17 is a view on line 17—17 in Fig. 16, partly in elevation and partly in section.

Referring to the drawings, which illustrate a preferred form of the invention, 10 generally indicates a cylindrical lock casing which is composed of two complementary sections 11 and 12. The meeting edges of these sections 11 and 12 are preferably undercut and overlap as at 13 to make 60 a tight joint between the sections. The section 12 has an internal flange 14 at one end provided with notches 15, and the section 11 has a ring portion 16 at one end provided with lugs 17 for disposition in the notches 15. Provided on the flange 14 are lugs 59 which fit in recesses 60 in the ring 16.

The section 12 has a ring portion 17' near its other end and the section 11 has a ring portion 18 superimposed over the ring portion 17' to close 75 one end of the casing when the sections are assembled; the sections 11 and 12 then being attached together by screws 20. It will be noted that the ring portions 17' and 18 have their confronting faces beveled so as to facilitate the assembling of the sections in casing formation, as shown in Fig. 3, and the assembling is brought about by shifting the sections with respect to each other in parallel planes in opposite directions for disposing the lugs in their respective 80 recesses. Apertures 21 are provided in the casing section 11 for the passage therethrough of elements for fastening the casing 10 to a support which may be, for example, the steering column 22 of a vehicle. The section 12 has a cut-out 85 portion or window 23 provided therein.

A substantially cylindrical supporting member or core 24 is located in the casing 10 and this supporting member 24 has an annular head 25 secured thereto by a set screw 19. Extending axially through the supporting member 24 is a bore 26 and also extending axially of the supporting member 24 is a slot 27 which opens inwardly into the bore 26. The supporting member 24 is provided between its ends, on its peripheral surface, with a series of spaced annular grooves 28 and with an axial groove 29 which extends parallel to the slot 27.

An annular tumbler 30 (Fig. 13) is arranged in each groove 28. Each of said tumblers 30 consists of two interfitting segments 31 and 32 and on the segment 31 is a key 33. Each tumbler 30 fits in an annular carrier 34 (Fig. 14) on an internal flange 35 of the carrier. The carrier 34 holds the two segments 31 and 32 of the tumbler to 105 110

gether and these carriers 34 encircle the supporting member 24. Provided on the flange 35 of each carrier 34 is a key 36 which fits in the groove 29.

5 A combination ring 37 is placed over each tumbler 30 and carrier 34 and these rings 37 encircle the supporting member 24. Each of these combination rings 37 has on one of its faces a series of radially arranged notches 38, 10 any one of which is adapted to receive the key 33 on the adjacent tumbler 30. Combination characters 39 are provided on the outer periphery of each combination ring 37.

The tumblers 30 being made in segments can 15 be readily placed in the annular grooves 28 in the supporting member 24 whereupon the carriers 34 may be placed over the tumblers to hold the tumblers in the grooves 28. The notches 38 in the combination rings 37 permit the rings 37 to 20 be latched to the tumblers 30 at different points so that the secret combination of the lock may be changed when desired.

The tumblers 30, carriers 34 and combination rings 37 are placed on the supporting member 25 24 and a retaining sleeve 40 is then placed on one end of the supporting member 24 and secured thereto by a set screw 41 which is arranged in a recess 43 in sleeve 40. The sleeve 40 thus retains the tumblers 30, carriers 34, and combination 30 rings 37 on the supporting member 24.

The retaining sleeve 40 is provided with an internal key 42 which fits into one end portion of the groove 29. A bearing lug 44 formed on the inner periphery of section 11 is disposed in the recess 43 in sleeve 40.

40 A locking bolt 45 is passed through a hole 46 in the ring 16, through the bore 26 in the supporting member 24 and through registered holes 55 and 47 in the rings 17 and 18. On one end of the locking bolt 45 is a knob or fingergrip 48. Provided in the bolt 45 is an axial slot 49 in which is disposed means in the form of a rack bar 50 to interlock with the tumblers. A spring 51 in the slot 49 projects the teeth of rack bar 50 into slot 27 of the supporting member 24. The rack bar 50 has end portions 51 which are connected to the bolt 45 by pin and slot connections 52.

50 Each of the tumbler segments 31 is provided with a notch 53, and the tumblers may be positioned with these notches 53 registered with the slot 27 so that the teeth of the rack bar 50 may be slid through the notches 53. However, by turning the tumblers 30 to a position in which their notches 53 are out of registration with the slot 27 the sidewalls of the teeth of rack bar 50 will engage portions of the tumblers and prevent the locking bolt 45 from being moved to a retracted position. Even though the notches 53 of the tumblers 30 may be out of registration with the slot 27 the bolt 45 can still be projected into locking position since in this case the beveled teeth on the rack bar 50 will engage portions of the tumblers and cause the rack bar 50 to move inwardly against the action of spring 51.

65 From the foregoing it will be seen that the bolt 45 may be moved to projected or locking position irrespective of the position of the tumblers 30; but that in order to retract the bolt 45 into unlocking position it is necessary that the tumblers 70 30 be so positioned that their notches 53 are registered with the slot 27. Thus it is necessary for one to know the proper combination of the characters 39 on the combination rings 37 before he can adjust the tumblers 30 to unlocking position.

Fig. 2 shows the unlocking combination as consisting of the aligned characters HKWA and to facilitate aligning of these characters the combination rings 37 are provided with parallel spaced lines 54.

80 The combination rings 37 may be easily turned by grasping those portions thereof that are exposed through the window 23.

It is to be noted that by passing the locking bolt 45 through the holes 46, 55 and 47 and by 85 engaging the lugs and recesses 17-15 and 59-60, the two sections 11 and 12 of the casing 10 are latched together so that it is impossible to gain access to the interior of the casing 10 by removing the screws 20.

The secret combination may be changed whenever desired by removing the supporting member 24 from the casing 10, then removing the ring parts on the supporting member 24 and reassembling the tumblers, carriers, and combination rings on the supporting member with the keys 33 of the tumblers engaged in different notches 38 in the combination rings 37 than those in which they were first engaged.

90 Figs. 16 and 17 show the lock used on a door 100 56. In this case the locking bolt 45 is projected through an aperture 57 in a keeper plate 58 attached to the door 56.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claim.

Having thus described my invention, what I claim as new and desire to protect by Letters Patent is:

110 A permutation lock comprising a casing including complementary sections having longitudinal overlapping edges, a ring portion providing the top wall of the casing and being integral with one section, a ring portion adjacent the corresponding end of the other section and formed integral therewith, said ring portions having confronting beveled faces and centrally disposed registering holes, a ring portion having a central hole therein and providing the bottom wall of 125 the first named section and formed integral therewith, lugs formed on the periphery of the last named ring portion and spaced from the side edges of its section to provide recesses, a flange formed integral with and following the inner curvature of the second named section at the lower end thereof and having recesses therein providing end lugs receivable in the first named recesses, with the first named lugs receivable in the second named recesses when the sections are 130 shifted in parallel planes in opposite directions for disposing the sections in casing formation, with the beveled faces confronting, a core in the casing, a locking bolt slidable in and through the core and the holes of the ring portions, permutation locking means on the core and bolt for securing the bolt fixed within the casing, and means including the permutation locking means for cooperation with the bolt and said lugs and recesses for fixing the sections in casing forma- 145 tion.

RAYMOND A. CRUSE.
